United States Patent Office.

B. WELLS DUNKLEE, OF BOSTON, MASSACHUSETTS.

Letters Patent No. 60,840, dated January 1, 1867.

IMPROVEMENT IN COAL STOVES.

The Schedule referred to in these Letters Patent and making part of the same.

TO ALL WHOM IT MAY CONCERN:

Be it known that I, B. WELLS DUNKLEE, of Boston, in the county of Suffolk, State of Massachusetts, have invented a new and useful Improvement in Air-Heating Furnaces; and I do hereby declare that the following to be a full, clear, and exact description thereof, reference being had to the accompanying drawings, making part of this specification, and in which—

Figure 1 is a top view.

Figure 2 a front elevation.

Figure 3, a side elevation.

Figures 4 and 5, vertical sections.

Figure 6 a horizontal section of an air-heating furnace constructed in accordance with my invention.

The objects which I accomplish by this invention being, first, to economize the amount of fuel consumed; second, to simplify the construction and regulation of the furnace; third, to intensify the current of air passing through the air-tubes; fourth, in the arrangement of the air-tubes surrounding the fire-pot. In the drawings—

A denotes the fire-pot; B the body of the furnace; C C, &c., all the body air-tubes; D D, &c., the cold-air extension of the said tubes; E the direct smoke outlet, F the indirect or downward smoke outlet, G the cut-off draught and clean-out door, H the upright connecting-pipe. The body air-tubes C are extended below the body of the furnace a sufficient distance to meet the lower strata of cold air admitted into the lower part of the chamber, in which the furnace is situated, for the purpose of taking up this cold air in separate columns and passing it upward through that portion of the air-tube situated within the body of the furnace, thereby securing a strong current of air through them, and consequently imparting a greater amount of heat to the air without liability of injury to the tubes; thus making the current of air more sure, steady, constant, and effective than can be accomplished without the extension of the said air-tubes into the cold-air chamber. The additional advantage of extending the air tubes below the body, and surrounding the fire-pot, is to evenly distribute the air that passes against the outside surface of the fire-pot, and is forced through the alternate spaces between the said air-tubes; these spaces being so arranged, or of such size, that the air must fill them, thus equally diffusing the heated air from this portion of the furnace. The pipe E, at its point of junction with the body of the furnace, is provided with a damper, I. When direct draught is required, this damper should be open, and the smoke will pass directly through the pipe E to the chimney. By closing the damper I the smoke will be caused to descend the driving-flue F into a horizontal smoke-flue, J, arranged as shown in the drawings, and with which the upright flues H and E communicate, and through which the smoke will ascend from flue J. This horizontal smoke-flue J is provided with an adjustable door, K, for the purpose of cleaning out the soot that may collect therein, as well as to regulate the inlet of cold air for the diminishing the draught through the pipe E. The location of the flues E F and J and the regulating-damper I, being in close proximity to the fuel supply door, renders the care and management of the furnace very easy and expeditious. This arrangement of the flues also secures a complete pressure of the products of combustion to all parts of the furnace.

I claim the arrangement of the combustion-chamber B with its smoke exits E F and H with respect to the air-tubes D D, &c., of the furnace, substantially in manner and for the purpose as above described.

I also claim the combination and arrangement of the flues E F and J, and their relative position with respect to the fuel-supply door of the furnace, essentially as set forth and explained.

B. WELLS DUNKLEE.
